Captain A. S. Young
ATTORNEY

UNITED STATES PATENT OFFICE.

EARL H. SHERBONDY, OF CLEVELAND, OHIO.

AIR-DELIVERY COOLER FOR TURBO-COMPRESSORS.

1,369,558.

Specification of Letters Patent. Patented Feb. 22, 1921.

Application filed April 30, 1918. Serial No. 231,768.

To all whom it may concern:

Be it known that I, EARL H. SHERBONDY, a citizen of the United States, residing at Cleveland, in the county of Cuyahoga and State of Ohio, have invented certain new and useful Improvements in Air-Delivery Coolers for Turbo-Compressors, of which the following is a specification.

This invention relates to a device for cooling air which has been compressed by a turbo-compressor, which turbo-compressor is adapted to be operated by the waste gases from an internal combustion engine, as described in detail in my co-pending case, Serial No. 224,356, filed March 23, 1918.

The turbine of the turbo-compressor is particularly designed for use on an airplane engine, to supply air under constant pressure to the carbureters of said engine, regardless of the height at which the airplane may be.

On account of the limitations of space in an airplane fuselage, the turbo-compressor unit must be small, which results in the blower casing of the compressor wheel being rather close to the gas casing of the turbine, and this results in the radiation of more or less heat to the blower casing, and the consequent heating of the air in said casing. Furthermore, simply compressing air, as is well known, raises its temperature; and due to the high speed of the compressor wheel, there is considerable friction and churning of the air, which still more tends to raise its temperature.

These facts result in the delivery of air from the compressor at too high a temperature for practicable use in the carbureter. It is the object of this invention to provide either air cooled means or water cooled means for cooling the compressed air, before its delivery to the carbureter.

Other objects and advantages will appear as the description proceeds.

In my copending case, Serial No. 234,558, filed May 14, 1918, I show an automatic, heat-operated control for use in a similar apparatus.

In the drawings, illustrating two embodiments of my invention, Figure 1 is a side view of an airplane engine with the turbo-compressor in place thereon connected to the cooling device, which latter is shown in section; Fig. 2 is a sectional view on the line 2-2 in Fig. 1; Fig. 3 is a view similar to Fig. 1, of a modified cooling device; Fig. 4 is a longitudinal sectional view of the cool-

ing device; and Fig. 5 is a sectional view on the line 5-5 of Fig. 4.

Referring now to Fig. 1, an airplane engine of the Liberty type water cooled, as is usual is shown, six only, however, of the twelve cylinders being shown. The crank case of the engine is indicated at 1, and the propeller shaft at 2. The turbo-compressor, designated generally 3, comprises the turbine casing 4 and blower casing 5. The turbine in the casing 4 is designed to be operated by the waste gases from the engine, which enter through the pipe 4', through a suitable port (not shown), which registers with the pipe 4', and escape through the pipe 6; the air for the blower wheel enters the mouth 5', is compressed, and is delivered into the delivery pipe 7.

The detailed structure of the wheels, nozzles and so on, of the turbo-compressor form no part of this invention, and are not shown here.

From the delivery pipe 7 the heated air passes into a cooler, comprising a casing 8, here shown as of an inverted U shape, but it obviously may be modified as desired. The ends 8' of said casing have mounted in them the open ends of a series of air tubes 9, which tubes are straight, arranged facing in the direction of travel of the airplane, and open rearwardly for the escape of the air after having passed through the tubes. The surfaces of these tubes will obviously be kept cool by the flow of air through them, due to the passage of the airplane through the air, and the hot air, in passing over these cooling surfaces, will obviously be adequately cooled.

A series of baffle plates 10 may be provided to cause a proper circulation of the hot air through the cooler casing. The air, after being cooled, passes into pipe 7', which leads it to the carbureters 11 and 12, preferably of the duplex type, the carbureters being connected in the ordinary way to the intake manifolds 13 and 14.

The cooler casing 8 is located on top of the fuselage 15, so as to be exposed to the atmospheric air.

In Fig. 3 a water cooled means for the air is shown, the other parts of the device remaining substantially the same.

The cooler, designated generally 16, comprises a casing 17, which is provided with a series of air and water passages, so arranged as to effect an exchange of heat between the

air and water. End plates 18 serve as mounting means for a series of concentric walls 19. Alternate annular spaces 20 are left open to provide passages for the air. 5 The other set of annular passages have their ends closed by the end plates 18, to provide a series of water passages 22, located intermediate the several air passages 20. The several water passages 22 communicate 10 with one another through the several pipes 22'. The water enters the lowermost part of the outer passage through pipe 23, which is connected to the radiator and water cooling system of the engine, the pipe 23 taking 15 the comparatively cool water just as it leaves the radiator on its way to the water jackets of the engine.

After the water has passed through the cooler 16, it escapes through the pipe 24, 20 and is delivered to the several pipes 25, which lead it to the water jackets of the several cylinders.

It will be evident that the surfaces of the air passages 20 will be kept cool by the water 25 just on the other side of the walls defining such passages.

In both forms of the invention, the heat taken from the hot air is delivered to the at-

mosphere, in the one case directly, and in the other case to a mass of water which in turn, 30 through the radiator, delivers it to the atmosphere.

While I have illustrated certain embodiments of my invention, it should be understood that the invention may be carried out 35 in other ways, as falling within the scope of the appended claims.

I claim:

1. In combination, a water cooled internal combustion engine, an air compressor to 40 supply compressed air for combustion in the engine, means to cool said air, and means to lead water from the cooling system of the engine to the cooling means, to act as the cooling agent therefor. 45

2. In combination, a water cooled internal combustion engine, a turbo-compressor operated by the waste gases from the engine to supply compressed air for combustion in the engine, means to cool the compressed 50 air, and means to lead water from the cooling system of the engine to said cooling means to act as the cooling agent in the said cooling means.

In testimony whereof I affix my signature. 55
EARL H. SHERBONDY.
